PROCESS FOR DYEING HAIR WITH SUBSTITUTED
2,4-DIAMINOPHENOLS

John Robert Seemuller, Maisons-Lafitte, Seine et Oise, France, assignor to L'Oréal, a corporation of France
No Drawing. Filed Dec. 7, 1959, Ser. No. 857,989
Claims priority, application France, Nov. 25, 1955,

5 Claims. (Cl. 167—88)

This application is a continuation-in-part of my pending application of Serial No. 623,773, filed November 23, 1956, which application is now abandoned.

This invention relates to the dyeing of animal fibres, and more especially the dyeing of live hair, by the use of polyaminophenol compounds and derivatives thereof.

It has long been known to effect the dyeing of hair with the aid of so-called "oxidation dyes," which are not true dyes but products which, on oxidation, give colored derivatives. The known "oxidation dyes" are generally aromatic polyamines and/or polyaminophenols.

Generally in using oxidation dyes a solution of such a dye is mixed, a short time before use, with an oxidizing solution, for example dilute hydrogen peroxide, and the mixture is then applied to the hair to be dyed. Satisfactory results are obtained, but this method offers the disadvantage that the treatment is of excessively long duration, the hydrogen peroxide tends to act deleteriously on the substance of the hair during the application, and it is necessary to store the working solutions in separate bottles.

It has now been found that polyaminophenols of the general formula:

wherein R₁ and R₂ designate a member of the group consisting of a hydrogen atom, a lower alkyl group or a lower hydroxyalkyl group; one or the other of the groups R₁ and R₂ must be other than hydrogen.

These compounds have remarkable properties as oxidation dyes for the dyeing of animal fibres and more especially of the human hair. The said compounds oxidize rapidly in the air so that the use of an auxiliary oxidizing agent, such as hydrogen peroxide, is avoided, together with the concomitant disadvantages referred to above.

According to the present invention therefore, a process for dyeing live hair comprises applying to the fibres a solution of a compound of the aforesaid general formula, allowing the oxygen of the ambient air to act on the hair impregnated with the compound for a time sufficient to the desired development of the shade, and thereafter rinsing the hair.

An aqueous solution of these compounds or of their derivatives is prepared, the pH of the solution is adjusted with the aid of an alkali, for example ammonium hydroxide, and the solution is applied to the fibres to be dyed, for example to the human hair. By simple exposure to the ambient air, the fibre is dyed to a shade depending upon the derivative chosen. The process is very simple, avoids the use of an oxidizing agent such as dilute hydrogen peroxide, and permits dyeing at room temperature.

The present invention further provides compositions for application to animal fibres for dyeing the same, comprising an aqueous solution of a compound of the aforesaid general formula adjusted to a pH value of 5 to 8.

2

EXAMPLE I

2-methylamino-4-aminophenol

10

Methyl sulphate is reacted in an alkaline medium with 2-amino - 4 - nitrophenol. 1 - methylamino-4-nitrophenol, melting at 110°—111° C., is thus obtained.

On reduction, the desired compound is obtained, which is isolated in the form of its sulphate.

Dyeing.—A 3% aqueous solution of the 2-methylamino-4-aminophenol sulphate is prepared and adjusted to a pH of 8 with ammonium hydroxide. This solution is applied to live hair and a light brown shade tinged with green, tending somewhat toward red, is obtained.

EXAMPLE II

4-beta-hydroxyethylamino-2-aminophenol

25

Potassium 2-nitro-4-aminophenate is condensed with glycol chlorohydrin in alcoholic solution. There is thus obtained 4-beta-hydroxyethylamino-2-nitrophenol melting at 114°—115° C.

Analysis:

Element	Calculated	Found
C.	48.5	48.3
H.	5.05	4.86
N.	14.14	14.21

This compound is then reduced to obtain the desired compound, which is isolated in the form of its sulphate, melting at 155° C.

Dyeing.—By operating under conditions similar to those of the foregoing example a beautiful violet shade is obtained on live hair.

EXAMPLE III
4-methylamino-2-aminophenol50

60 This compound is prepared in the following manner: N-methyl-para-aminophenol is acetylated, then nitrated by the classical method. Then it is deacetylated to obtain the 4-methylamino-2-nitrophenol, which gives by reduction using the usual technique, the 4-methylamino-2-aminophenol which is isolated as the sulphate.

65 *Dyeing.*—This material is used in a manner analogous to that described in the preceding examples. A 3% sulphate solution is applied to live human hair having a pH adjusted to 8 by the addition of ammonium hydroxide. This allows the dyeing of white hair a deep blue shade.

70 In order to clearly show the particular possibilities of the use of the compounds according to the invention, all

the dyeing tests described in the foregoing examples were carried out without any oxidizing agent other than atmospheric oxygen.

What is claimed is:

1. A process for dyeing live human hair which comprises: applying to the hair an aqueous solution as an oxidative dye stuff of a compound of the formula

wherein R₁ and R₂ are selected from the group consisting of hydrogen, lower alkyl and lower hydroxy alkyl, and at least one of R₁ and R₂ are other than hydrogen, thereafter said hair is aerated to promote the substantial oxidation of this compound before being rinsed.

2. A process for dyeing live human hair which comprises: applying to the hair an aqueous solution as an oxidative dye stuff adjusted to a pH of 5 to 8 of a sulphate of a compound of the formula

wherein R₁ and R₂ are selected from the group consisting of hydrogen, lower alkyl and lower hydroxy alkyl, and at least one of R₁ and R₂ are other than hydrogen, thereafter said hair is aerated to promote the substantial oxidation of this compound before being rinsed.

3. A process for dyeing live human hair which comprises: applying thereto an aqueous solution as an oxidative dye stuff containing 2-methylamino-4-aminophenol, thereafter said hair is aerated to promote the substantial oxidation of this compound before being rinsed.

4. A process for dyeing live human hair which comprises: applying thereto an aqueous solution, as an oxidative dye stuff, containing 4-beta-hydroxyethylamino-2-aminophenol, thereafter said hair is aerated to promote substantial oxidation of this compound before being rinsed.

5. A process for dyeing live human hair which comprises: applying thereto an aqueous solution, as an oxidative dye stuff, containing 4-methylamino-2-aminophenol, thereafter said hair is aerated to promote the substantial oxidation of this compound before being rinsed.
